UNITED STATES PATENT OFFICE.

HERMANN G. DITTBENNER, OF MINNEAPOLIS, MINNESOTA.

WATER-PURIFIER.

No. 917,933.

Specification of Letters Patent. Patented April 13, 1909.

Application filed June 6, 1908. Serial No. 437,113.

To all whom it may concern:

Be it known that I, HERMANN G. DITTBENNER, a citizen of the United States, residing at Minneapolis, in the county of Hennepin and State of Minnesota, have invented certain new and useful Improvements in Water-Purifiers; and I do hereby declare the following to be a full, clear, and exact description of the invention, such as will enable others skilled in the art to which it appertains to make and use the same.

My invention has for its especial object to provide an improved hot water purifier with an automatic thermally-actuated valve for controlling the flow through the same; and to the above ends the invention consists of the novel devices and combinations of devices hereinafter described and defined in the claims.

In the accompanying drawings which illustrate the invention, like characters indicate like parts throughout the several views.

Referring to the drawings, which illustrate the improved device in what at present is believed to be its preferred form, Figure 1 is a view, chiefly in vertical section, taken through the device on the line $x^1 x^2$ of Fig. 2, some parts being left in full. Fig. 2 is a transverse section taken on the irregular line $x^2 x^2$ of Fig. 1; and Fig. 3 is a transverse vertical section taken on the line $x^3 x^3$ of Fig. 1.

The body or external portion of the device is in the form of a cylindrical or tubular metal shell 1 having closed ends, one of which ends 35 is closed by a detachable screw-threaded head 2, and the other head of which is tapped by a coupling 3, the particular construction of which will be noted later on. Near its ends the shell 1 is provided with coupling sleeves 4 and 5 that open tangentially into the interior of said shell, and the former of which may be assumed to be connected to and to receive hot water from the coil of a furnace or water back of a stove, while the latter may be assumed to be connected to an ordinary hot water tank, which tank should be connected to the hot water coil or hot water back for the return of the relatively cold water thereto. Otherwise stated, this shell 1 is connected in the hot water delivery pipe that extends from a hot water coil or water back to a hot water tank, or similar hot water heating apparatus. The importance of

the tangential arrangements of the coupling sleeves 4 and 5 will be considered later on. 55 Near one end the shell 1 is further provided with a third coupling sleeve 6 that will usually be connected to the kitchen and bathroom hot water faucets. The numeral 7 indicates a hot water thermometer of standard construction, which is screwed into a sleeve 8 of the shell 1.

Located within the shell 1 and screwed into and rigidly supported by the coupling 3 is a sleeve 9 that is externally threaded at both 65 ends.

Located concentric to and within the shell 1 is a hollow spool 10 having enlarged hollow heads 11, both of which heads are formed with hubs, one of which is screwed onto the 70 threaded inner end of the sleeve 9, and the other of which has a threaded axial perforation that is closed by an adjustable plug 12. Preferably this spool 10 is made of aluminum. A small tube 13, preferably of iron, is 75 screwed, at one end, into the adjustable plug 12 and extends axially through the entire spool 10 and its heads 11, and entirely through the fixed supporting sleeve 9, which latter, it will be here noted, supports the entire spool 80 and parts carried thereby. The contracted body portion of the spool 10 is provided with a multiplicity of radial perforations 14, through which water may freely pass. A very great portion of the small tube 13 is 85 closed by a long wooden plug or rod 15, but beyond the inner end of said plug said tube is provided with a multiplicity of radial perforations 16 that are preferably covered by a body of mineral wool or similar material 17. 90

Immediately surrounding the contracted body portion of the spool 10 and extending between the heads 11 thereof, is a cylindrical layer of mineral wool 18 that is completely surrounded by a cylindrical cover 19 of asbestos paper, which latter is held in place by a helically wound copper wire 20 that is preferably tinned. Immediately surrounding the wrapper 19 and coiled wire 20 is a cylindrical body of charcoal 21 that is contained 100 within a cylindrical wrapper 22 of asbestos paper held in place by a coiled copper wire 23, that is also preferably tinned. A heavy cylindrical body of asbestos wool 24 surrounds the wrapper 22 coiled wire 23, and 105 this is contained within a reticulate retaining

cylinder and strainer 25, preferably in the form of a tinned copper wire netting of very fine mesh.

The above is a preferred arrangement of 5 concentric straining media, but this arrangement, of course, may be varied, especially in respect to the substitution of the materials.

The small tube 13 is capable of slight end- 10 wise sliding movement through the fixed sleeve 9, and a water tight joint is formed between the said parts, by means of a stuffing 15 box 26. A small valve 27, made up of a stem and a head normally closes the outer end of the said tube 13, the stem of said valve being of considerably less diameter than the interior bore of said tube. The head of said valve is normally engaged and held in a closed position by an adjustable abutment in the form of a long set screw 28 that works 20 through and has threaded engagement with the coupling 3 and is axially alined with the tube 13 and valve 27. A stuffing box 29 affords a water tight joint between the set screw 28 and the coupling 3. A hot water 25 delivery pipe 30 extends upward from the coupling 3, and a water tight joint is formed between the said parts by a stuffing box 31. The outer end of the tube 13 and its valve 27 are located within a recess 32 of the coupling 3, and this recess is connected to the water 30 delivery pipe 30 by a small port 33 that is normally closed by a check valve in the form of a ball 34. The water delivery pipe 30 may extend to any suitable point, but will 35 usually be connected to a suitable tank or receptacle provided for the purified and sterilized water.

In view of the fact that the spool 10 is constructed of aluminum, which has a greater 40 factor of expansion under increasing temperature than the iron tube 13, and further in view of the fact that the heads 11 of said spool will increase its longitudinal expansion, and since the said tube 13 is anchored by 45 the plug 12 to the free head of the said spool, it is evident that when the said spool and tube are both subjected to hot water of some certain temperature, the outer end of the tube 13 will be moved away from the valve 50 abutment or set screw 28 so as to permit the valve 27 to open up the outer end of the said tube 13 and permit an outward flow of hot water upward through the port 33 and water delivery pipe 30. The temperature at which 55 this opening of the valve 27 will occur may be varied by adjustments of the abutment screw 28 or of the plug 12. Usually this adjustment will be such that the valve 27 will open only when the temperature of the water is 60 above 212 degrees, which is the boiling point of water at atmospheric pressure. The said valve being thus set, a discharge of sterilized water through the pipe 30 will occur whenever and only when the temperature of the 65 water is above 212 degrees, which insures

sterilization. This discharge of sterilized water is, therefore, completely automatic.

There will, of course, be a continuous circulation of water through the shell 1 under the action of convection, and this circulating 70 water from the hot water coil enters the shell 1 through the tangential coupling sleeve 4 and leaves the said shell on its way to the hot water tank through the tangential discharge sleeve 5.

It is here important to note that the arrangement of the tangential coupling sleeves 4 and 5 are such that the water, in passing from the former to the latter, will circulate helically in the cylindrical space between the 80 shell 1 and the screen 25, and this insures a motion of the water in all portions of the said shell and thus prevents the accumulation of sediment.

Regardless of the temperature of the 85 water, water for ordinary uses may be drawn off through the sleeve 6 by opening of hot water faucets in the kitchen, bathroom, or elsewhere. Sterilized water which passes from the shell 1 to the delivery pipe 30 must 90 first pass through the screen 25, thence through the outer layer of mineral wool 24, thence through the outer asbestos paper wrapper 22, thence through the body of charcoal 21, thence through the inner asbestos wrapper 19, thence through the perforations 24 in the spool 10, thence through said spool and through the asbestos body 17 and perforations 16 into the small tube 13, and from the latter through the chamber 32 and 100 port 33 of the coupling 3 into the said water delivery pipe 30. In thus passing through the several concentric straining or filtering media, the water will be thoroughly purified, that is, all solid foreign materials will be removed from the water. In fact, nearly all of 105 these impurities will be lodged on the outer surface of the outer layer of mineral wool 24, and all large particles will be stopped by the screen 25 before they reach the said layer 24, 110 and hence will be ultimately carried off through the general service connection or sleeve 6, or will be deposited in the hot water tank. The opening in the end of the shell 1 which is normally closed by the cap or head 115 2 is large enough to permit the spool 10—11 to be inserted into said shell or removed therefrom. As shown in Fig. 1, the head of the valve 27 is slit so that by the application thereto of a screw-driver it may be rotated 120 for the purpose of grinding it onto the seat afforded by the end of the sleeve 13.

The strainer or filtering device is, of course, capable of use independently of the automatic valve mechanism for regulating 125 the flow therethrough; and it may, of course, be thus used either for cold or warm water. Furthermore, the device is capable of being used for controlling the flow of steam or the flow of water condensed from 130

steam. In fact, whether or not the moisture will be in the form of water or steam will depend on the pressure under which it is confined and the temperature at which the automatic valve is set to be opened and closed.

5. What I claim is:

1. In a water purifier the combination with a shell having tangential inlet and outlet passages located one at each end thereof, and so extended as to coöperate to produce 10 helical motion of the water in the same direction, of a straining device extended axially within said shell and a pure water outlet tube extending from the interior of said straining device to the exterior of said shell.

15. 2. In a water purifier, the combination with a cylindrical shell having an inlet passage opening tangentially into one end portion thereof, and an outlet passage opening tangentially outward from the other end portion thereof, of a straining device within said shell made up of a perforated hollow metal spool and concentric layers of straining media surrounding the same, and a pure 20 water outlet tube extending from the interior of said spool axially outward through the same and through said shell, substantially as described.

25. 3. In a device of the kind described, the combination with a shell having suitable inlet and outlet passages for the circulation of hot water, of a straining device within said shell, a pure water outlet tube extending from the interior of said straining device to the exterior of said shell, a valve for controlling the flow of water through said outlet tube, and thermally actuated means for opening and closing said valve, whereby the 30 automatic control of purified water at predetermined temperature is afforded, substantially as described.

35. 4. In a device of the kind described, the combination with a shell having suitable inlet and outlet passages for the circulation of

hot water, of a perforated metal spool located 45 within said shell and anchored thereto at one end, filtering media surrounding the perforation portion of said spool, a pure water outlet tube with one end extending axially outward through the anchored end of said spool, 50 and with its other end anchored to the free end of said spool, a valve for closing the outer end of said pure water tube, an abutment holding said valve closed when the water is below a predetermined temperature, and the 55 said metallic spool serving, by endwise expansion, to open said valve, when the water is above a predetermined temperature, substantially as described.

5. In a device of the kind described, the 60 combination with a shell having suitable inlet and outlet passages for the circulation of hot water, of a hollow metallic spool having enlarged hollow ends or heads and having perforations in its contracted body portion, the 65 said spool being located within said shell and anchored thereto at one end, filtering media surrounding the perforated body portion of said spool, a pure water outlet tube with one end extended axially outward through the 70 anchored head of said spool and with its other end anchored to the free end of said spool, a valve for opening and closing the outer end of said pure water tube, and an adjustable abutment holding said valve 75 closed when the water is below a predetermined temperature, and the said metallic spool serving, by expansion, to open said valve when the water is above a predetermined temperature, substantially as de- 80 scribed.

In testimony whereof I affix my signature in presence of two witnesses.

HERMANN G. DITTBENNER.
